SAFETY DEVICE

Vernie A. Fox, Detroit, Mich.

Application October 3, 1941, Serial No. 413,408

4 Claims. (Cl. 292—79)

This invention relates, in general, to safety devices and, in particular, to those employable in conjunction with the door openings of heat compartments, such as ovens.

One of the objects of the present invention is to provide a new and improved safety device capable of meeting and overcoming the dangers which inevitably accompany inadvertently built-up pressures within a compartment heated by the burning of a combustible fuel, such as gas.

Another object is to provide a new and improved safety device for the door of a compartment by the use of which said door is permitted to open freely and automatically when the pressure within said compartment reaches a predetermined value.

Another object is to provide a new and improved safety device for the door of a compartment in which excessive pressures may be inadvertently built up, said device being inexpensive in construction and assembly and faultlessly operable automatically to permit the free opening of said door when said pressures are reached.

Another object is to provide a new and improved safety device which is operable for effectively and safely relieving excessive pressures built up within a heating compartment, and which device is easily and readily adjustable to meet different pressure conditions.

Another object is to provide a new and improved pressure-relieving safety device which may be employed as easily and effectively with a used heating compartment as with a new heating compartment, and vice versa.

Other objects and advantages of the invention will become readily understood from a reference to the following specification taken in conjunction with the accompanying sheet of drawings wherein:

Figure 1 is an elevational view of a door-receiving wall of a heating compartment and shows the door in closed position and the elements of the novel safety device in operative positions, parts of said figure being broken away and in section to illustrate more clearly some of the details of the construction thereof;

Figures 2, 3 and 4 are sections taken along the lines 2—2, 3—3 and 4—4 respectively in Figure 1; and

Figure 5 is an elevational view similar to but smaller than that shown in Figure 1 and shows a door employing two of the devices shown in said Figure 1.

The safety device described herebelow and shown herewithin finds utility principally in conjunction with compartments which are heated by

the combustion of fuel such as gas, and which gas, through inadvertence, might not be ignited, in which event, excessive pressures would be built up. The safety device finds its use with this type of compartment in that it enables the door to open automatically to bring about relief of the dangerously high pressures. Such a compartment is usually heat insulated through the use of composite wall structures, one of these walls being shown at 10 and said wall being provided with an access opening 12 along one side of which a door 14 is hinged for swinging into or out of said opening to close or open the compartment residing on the other side of said wall.

The edge of door 14 opposite the edge carrying the hinges therefor which are shown at 16 has fixed thereto in any suitable manner the upper and lower flanged portions 18 and 20 of a rectangularly shaped box-like structure, generally indicated at 22. Structure 22 includes horizontally spaced, vertically extending, front and rear walls 24 and 26 and vertically spaced upper and lower horizontally extending walls 28 and 30, said upper and lower walls and said front and rear walls defining a rectangular space 32. It will be noted that the side of structure 22 which is opposite the hinged side of door 14 is open and substantially flush with the adjacent side of said door.

Space 32 which is confined within the various wall elements of structure 22 is adapted for receiving an elongated rectangular rod 34 one end of which carries a pivot pin 36 which is journaled in the front and rear walls 24 and 26 of said structure to permit movement of said rod about the horizontal transverse axis of said pin, the opposite end of said rod being reduced in cross section to provide a cylindrically shaped portion 38 which extends outwardly of said space into overlying relationship with the adjacent portion of compartment wall 10. In view of the length of rod 34 and of its movability about pin 36 relatively to walls 24 and 26, it has been found desirable to make the width of said rod less than the inner spacing between said walls, so that during movement of said rod, there will be little or no contact with said walls. However, rod 34 should be guided in its movement about pin 36 and, for this reason, a roller 40 is freely arranged about the inner end of cylinder 38 in abutment with the outer end of said rod, whereby said roller provides a substantially antifriction connection with walls 24 and 26.

Whereas walls 24 and 26 of structure 22 carry pin 36 about which rod 34 is movable, walls 28 and 30 of said structure are adapted, respec-

tively, to support the head end and threaded lower end of a vertically arranged bolt 42, said rod being formed with an opening 44 through which said bolt is freely received. It will be noted that opening 44 is large enough to prevent any interference between bolt 42 and rod 34 during movement of the latter about pin 36, and it will also be noted that such movement of said rod is normally in a clockwise direction due to the provision of a spring 46 which is telescopically arranged about said bolt with its upper end in abutment with the lower face of said rod and its lower end in abutment with the upper face of a nut 48 threadedly received on the lower end of said bolt for adjustment therewith to effectuate variable tensioning of said spring.

Cylindrical portion 38 of rod 34, in addition to carrying roller 40, carries another roller 50 which is to serve, as will be seen, as a cam follower, and between said rollers said cylindrical portion preferably carries a rotatable filler 52, said rollers and said filler being held against displacement from said cylindrical portion by means of a washer 54 which is held in place in any suitable manner at the extreme outer end of said cylindrical portion.

The portion of compartment wall 10 residing directly above roller or cam follower 50 carries a plate 56 with which is integrally formed a forwardly extending, vertical, cam-forming portion 58 which at its inner, lower corner is spaced from said compartment wall to provide a rearwardly inclined cam surface 60 directly overlying a substantially central portion of roller 50. It will be noted that element 56 of unit 56-58-60 is adapted for adjustable positioning in a vertical direction, but this construction is not necessary and is shown purely for the purpose of illustration, since any adjustability between cam surface 60 and cam follower 50 may be taken care of by adjusting the vertical positioning of nut 48.

Upon adjusting the tension of spring 46 by manipulation of nut 48 with respect to the pressure which is to be deemed the critical pressure within the heating compartment, door 14 may be closed by manually lowering the rod 34 so that roller 50 will miss element 58 of unit 56-58-60. After door 14 has been so closed, conditions may arise within the heating compartment which would possibly raise the pressure to or above aforementioned critical pressure, in which event this pressure would force the door outwardly and cause roller 50 to roll along or follow cam surface 60, the while forcing rod 34 downwardly against the pressure of spring 46 until said roller would clear the lower end of said cam surface and permit said door to open fully the access opening 12. Of course, pressure relief may be brought about by the slightest opening of door 14 but, whether relief is obtained by the roller 50 fully or only partially clearing the end of cam surface 60, relief is nevertheless safely, automatically and faultlessly had.

Although the invention has been described with some detail, it is to be understood that such description is for the purpose of illustration only and is not to be taken as definitive of the limits of the inventive idea. The right is reserved to make such changes in the details of construction and arrangement of parts as will fall within the purview of the attached claims.

What I claim is:

1. A device of the character described including, a keeper secured to a wall having an open-

ing therein and which keeper is formed with a pair of cam surfaces angularly related to the wall and to one another, a latch bar having one end pivotally carried by and movable with a closure member for the opening and which latch is formed with a follower portion on the free swinging end thereof movable along said cam surfaces responsive to movement of the member, said follower having an extension for engaging the edge of the door and being guided thereby, means cooperable with said latch intermediate the ends thereof for exerting a pressure thereupon to oppose movement of said portion along said cam surfaces in one direction, and means selectively operable for varying said pressure.

2. A device of the character described including, a plate member secured to a wall having an opening therein and which member is formed with a forwardly extending portion having a rearwardly inclined cam surface and a forwardly inclined cam surface, a latch having one end pivotally carried by a movable closure member for the opening for movement therewith as well as for movement about an axis and which latch is formed with a follower portion on its free swinging end movable along said surfaces about said axis responsive to movement of the closure member, said follower portion having formed thereon a door engaging guide and resilient means intermediate the ends of the latch operable for urging said follower portion toward the upper end of said surfaces.

3. A device of the character described including, a keeper secured to a wall having an opening therein and which keeper comprises a forwardly extending portion having forwardly and rearwardly inclined cam surfaces, a casing support carried by a movable closure member for the opening, a latch having one end pivoted to said support for movement about an axis and with the member and having a follower portion on the free end thereof movable along said cam surfaces about said axis responsive to movement of the closure member a guide member adjacent the follower engaging the casing support, a threaded adjusting bolt projecting into and carried by said support, a spring carried by said adjusting bolt in engagement with said latch for urging said follower portion toward the upper end of said surface and a nut on said bolt engaging the opposite end of said spring.

4. A device of the character described including, a keeper secured to a wall having an opening therein and which keeper comprises a forwardly extending portion having a rearwardly and forwardly inclined cam surfaces, a casing support carried by a movable closure member for the opening, a latch bar having one end pivoted to said casing support for movement about an axis and with the member and having a follower portion on the free swinging end movable along said cam surfaces about said axis responsive to movement of the closure member, a guide roller on said follower portion engaging said casing, a threaded adjusting bolt extending into and carried by said casing support, a spring carried by said adjusting bolt in engagement with the intermediate portion of said latch for urging said follower portion toward the upper end of said surfaces, and an adjustment nut threaded on the bolt operable for varying the pressure of said spring.
